[57] CLAIM

I claim the ornamental design for a plastic bottle, as shown and described.

DESCRIPTION

FIG. 1 is an elevation view of the back of a plastic bottle of the present invention.

FIG. 2 is a right side elevation of the plastic bottle, the left side elevation is a mirror image thereof.

FIG. 3 is an elevation view of the front of the plastic bottle shown in the prior figures.

FIG. 4 is a top plan view of the bottle shown in the prior figures.

FIG. 5 is a bottom plan view of the bottle shown in prior figures; and,

FIG. 6 is a sectional view of the bottle taken along line 6—6 of FIG. 2.
